(57) **CLAIM**

The ornamental design for a caddy for electronic devices, as shown and described.

DESCRIPTION

FIG. 1 is a right side view of a caddy for electronic devices, showing my new design.

FIG. 2 is a front side view thereof, the rear side view being a mirror image.

FIG. 3 is a top perspective view thereof.

FIG. 4 is a bottom view thereof.

FIG. 5 is a left perspective view.

FIG. 6 is a right perspective view; and,

FIG. 7 is a perspective view thereof from the left and from above.

The broken lines are for the purpose of illustrating the environment of the design only, and form no part of the claimed design.
